Jack J. Bayer, Los Angeles, Calif.

Application March 8, 1954, Serial No. 29,410

Term of patent 14 years

(Cl. D88—3)

To all whom it may concern:

Be it known that we, Jacob J. Entin, Louis Goodman, and Jack J. Bayer, all citizens of the United States, residing at Los Angeles, in the county of Los Angeles and State of California, have invented a new, original, and ornamental Design for a Metal Umbrella, of which the following is a specification, reference being had to the accompanying drawing, forming part hereof.

Fig. 1 is a view in side elevation of the umbrella embodying our new design, the lower portion of the mast thereof being broken away for convenience of illustration; and

Fig. 2 is a perspective view of the metal umbrella embodying our new design.

We claim:

The ornamental design for a metal umbrella, as shown and described.
